UNITED STATES PATENT OFFICE

ARTHUR J. MUNDY, OF BOSTON, MASSACHUSETTS, ASSIGNOR TO SIRINE SIGNAL COMPANY, OF WATERVILLE, MAINE, A CORPORATION OF MAINE.

SOUND TRANSMITTER AND RECEIVER.

SPECIFICATION forming part of Letters Patent No. 768,570, dated August 23, 1902.

Application filed April 23, 1902. Serial No. 104,299. (No model.)

To all whom it may concern:

Be it known that I, ARTHUR J. MUNDY, a citizen of the United States, and a resident of Boston, in the county of Suffolk and State of Massachusetts, have invented a new and useful Improvement in Sound Transmitters and Receivers, of which the following is a full, clear, and exact description, reference being had to the accompanying drawings, forming a part of this specification, in explaining its nature.

My present invention relates to submerged means for receiving sound-vibrations imparted at a distance to the water in which said means is submerged and transmitted by such water to said receiving means.

It has heretofore been believed that to obtain first-class results the diaphragm of the receiving-transmitter should be in direct contact with the open water or medium by which the sound was being transmitted and that the interposition of anything between the diaphragm and the open water impaired the effectiveness of the instrument. The efforts made in the past, however, to maintain the transmitter in contact with the transmitting medium have necessitated the adoption of apparatus having inconveniences and faults commensurable to those sought to be avoided. Delicate receiving instruments have been suspended directly in the open sea or have been mounted in the sides of ships and other vessels; the unprotected diaphragm being in all such instances liable to damage from floating and other obstacles and other sources of injury. Moreover, such apparatus when used in connection with ships presents when suspended from the ship the additional difficulty of keeping it submerged when the ship is moving or in flowing tides or currents, or when mounted in the side of the ship the difficulty of securing clear signals owing to the interfering noises created on shipboard and conveyed to the transmitter through the shell of the ship.

I have discovered that it is possible to encase the transmitter without injuriously affecting its responsiveness to sound-waves and

by the shell of the casing to protect damage from exterior agencies. The ship may constitute a portion of such protecting-shell and the ship, in such is the casing itself. In such case I prefer the use of a transmitter entirely within the ship, this being my preferred construction when my invention is used on shipboard.

I have discovered that although energy in sound-waves is ordinarily lost in passing from one medium to another, yet it is possible to interpose between the receiving-diaphragm and the source of sound a protecting shell, provided that the continuity of the transmitting medium is otherwise substantially unbroken—that is to say, if the medium said interposed casing be of similar nature that without, then, as a matter of fact, is no material change in the transmitting medium, and consequently no material loss of energy in the transmission. Actual experiments and use have demonstrated that the interposed shell apparently does not interfere with the passage of the waves through it, and that it delivers to the liquid upon one side substantially the impulses received from the water on the other side.

In the location of the transmitter upon board there is employed within the ship, preferably against the side thereof, the shell or side of the ship preferably as one wall of the tank. This tank is one of the water-ballast tanks of the ship, may be a specially-constructed tank, or in contact with the liquid of the interior tank the receiver, which may be of any desired type, is suitably suspended and otherwise mounted, and when so mounted in the side of the ship the difficulty of securing clear signals owing to the interfering noises created on shipboard and conveyed to the transmitter through the shell of the ship have heretofore interfered with the transmission of the signals, confused the actual signals in instruments where the transmitters have been mounted.

directly in or on the walls of the ship. Such noises are apparently not delivered to the liquid of the tank in such a way as to affect my transmitter suspended therein. The signals-waves, however, striking the side of the ship pass through and into the tank, where they are collected by the transmitter and delivered to the operator. The use of a body of liquid within a casing as a means for receiving and transferring sound-vibrations imparted to the water without is also of value in that it permits of the employment of fresh water or other non-corroding liquid in contact with the transmitter, and it also permits of the pressure to which the transmitter is to be subjected being determined in advance, that it may be constructed to meet the requirements of such pressure, and in that it provides the transmitter with a constant pressure instead of a variable one, as is the case where the transmitter is used free or unrestrained in the outer water.

I shall describe the use of my invention in connection with a ship, and for a clearer explanation thereof reference is made to the following drawings, in which—

Figure 1 illustrates a steam vessel, bow on, with a portion removed to show the forward ballast-tank and the electrical transmitter contained therein. Fig. 2 is an end view, partly in cross-section, of the submerged receiving means.

Referring to the drawings, A represents a tank within a ship; α , the water therein; B, the shell of the vessel; C, the water in which it floats and moves, and D an electrical transmitter contained in the water-ballast tank and submerged in the water therein. This transmitter of the sound or signal vibrations is preferably electrical, and the one shown is that described in my copending application for Letters Patent of the United States, Serial No. 104,297, and need not be specifically described here, it being sufficient to say that the vibrations communicated to the water by the submerged signaling apparatus are transferred by the water and through the shell of the vessel to the water in the tank and by it to the diaphragms of the transmitter, and these diaphragms receive and electrically transfer them to the receiver E, which may be located in any part of the vessel. In the drawings it is represented as in the pilot-house of the vessel.

Having thus fully described my invention,

I claim and desire to secure by Letters Patent of the United States—

1. As a means for transmitting sound-solutions transferred from a sound-signaling station through water, a liquid, sound-transmitting medium contained in a tank holder within a ship or other vessel, said medium being located to receive solutions transferred by the water in the ship or other vessel floats, and a sound-transmitter in contact with said medium contained in said tank or other holder, and electrically connected with a receiving apparatus.

2. In a means for transmitting sound-solutions through water from a sound-station, a liquid sound-transmitting medium contained in a tank or other holder within a ship or other vessel in said water, said medium being located therein to receive sound-solutions so transferred by the water in the ship or other vessel floats, and a sound-transmitter in contact with said liquid contained in said tank or other holder.

3. As a means for transmitting sound-solutions transferred from a sound-signaling station through water, a comparative sound-transmitting medium contained in a tank or other holder within a ship or other vessel in said water, said medium being located to receive and transmit sound-solutions transferred thereto by the said water through the shell of the ship or vessel.

4. As a means for transmitting sound-solutions transferred from a sending-station through water, a liquid vibration-transmitting medium contained in a holder within a ship or other vessel in said water and located to receive the vibrations, transferred through the water, through the shell of the ship or vessel to it.

5. As a means for transmitting sound-solutions transferred from a sending-station through the water, a receptacle in contact with the water, a liquid vibration-transmitting medium contained in said receptacle, a sound-transmitter in contact with the transmitter, a sound-drum in the receptacle, said medium being located between said transmitter and the wall of the receptacle in contact with the outer water, and a receptacle shielding the transmitter from the outer water.
